UNITED STATES PATENT OFFICE.

WILFORD J. HAWKINS, OF MONTCLAIR, NEW JERSEY, ASSIGNOR TO AMERICAN MACHINE AND FOUNDRY COMPANY, A CORPORATION OF NEW JERSEY.

CIGARETTE AND METHOD OF MAKING THE SAME.

Application filed August 29, 1924. Serial No. 734,950.

This invention relates to an improved cigarette and method of making the same.

In making cigarettes having fillers of shredded tobacco, it has heretofore been customary to arrange a mass of tobacco leaves in superposed condition in a shredding machine, and then slice from the mass a series of straight shreds, by means of a reciprocating knife having a flat surface and a straight edge, the mass being advanced about $\frac{1}{16}$ of an inch between knife reciprocations, so that shreds of this width are produced. The shreds so produced receive further treatment which lies outside the range of the present invention but during which they are separated and then reassembled in a more or less fluffy entangled mass.

In open end cigarettes having shredded filler, whether produced by hand, or by machine, methods, the tobacco must so adhere to the paper wrapper that the tobacco will not fall out thereof. It does this by expanding within the wrapper after having been introduced thereinto in a slightly compressed condition and then released. But in order to effect this adherence an excess of tobacco filler or shreds is essential which, otherwise, would not be required. The inclusion of the excess tobacco interferes somewhat with the free draft that is desirable.

It has now been discovered that a saving of upwards of 10% of the tobacco filler or shreds heretofore required, and improved draft, may be effected by making the cigarette of a wrapped filler containing crinkly shreds of tobacco, instead of the straight shreds heretofore used. Crinkly shreds, as used herein, means shreds having a series of short, artificially-produced, inherent bends or wrinkles. Such a cigarette may be produced by first cutting tobacco to form crinkly shreds, which of course are longer than straight-cut shreds and therefore better, and subsequently forming filler containing such shreds and wrapping said filler, either simultaneously as in making cigarette of the continuous rod type, or consecutively as in making individual cigarettes. The main object of the present invention is the production of such a cigarette and method of making the same, in order to effect the industrial economy above indicated, and in order to produce better cigarettes.

In the accompanying drawings, which form a part of this specification and in

which like characters of reference indicate the same or like parts, Fig. 1 is a sectional elevation of a part of a shredding machine, the section being taken on the line 1-1 in Fig. 2 which is a front elevation of the machine; Fig. 3 is a detail sectional view of the slicing knife and ledger plate used in the machine shown in Figs. 1 and 2; Fig. 4 is a front elevation of the devices shown in Fig. 3; Fig. 5 is a cross-sectional view of the parts shown in Figs. 3 and 4; Fig. 6 is a plan view of a mass of superimposed tobacco leaves as placed in the shredding machine, and illustrating two shreds separated from the mass; and Fig. 7 is a perspective view of a cigarette made in accordance with the invention, the same being partly broken away to show the crinkly-cut shreds of the filler within the wrapper.

Referring to the drawings, 8 and 9 are the coacting feed rollers of a tobacco shredding machine having a feed throat 10 just ahead of said rollers. Following the usual practice in the operation of such shredding machines, a mass of superposed tobacco leaves 11 is placed in the shredding machine just behind the rollers 8 and 9, and this mass is compressed and forced through the feed throat 10 at proper intervals, the feeding movements being approximately $\frac{1}{16}$ of an inch each.

This shredding machine has a reciprocating knife for slicing the tobacco into shreds. The knife itself, however, differs from the flat-surfaced and straight-edged knives heretofore used to shred tobacco. It is shown at 12 as having not a flat surface and a straight edge but a serrated surface and edge. The surface and edge of such knives may be varied to vary the exact form of the shreds produced thereby. The knife coacts with a ledger plate 13 having a serrated, or other, surface corresponding to that of the knife. The plate 13 surrounds the feed throat 10 through which the mass of tobacco is forced. The knife is reciprocated by means of a crank shaft 14 and connected yoke 15, in the usual manner. The reciprocations occur during the intervals between feed movements, and the result of each knife operation is the production of a shred which is crinkly-cut without stressing the tobacco, so that the shred will retain its crinkly characteristic during subsequent operations. It is to be understood that when the knife operates on a mass

of superposed tobacco leaves, a number of similar shreds will be cut simultaneously therefrom during each knife operation. Such collocations of shreds are shown at 16 5 in Fig. 6.

After the tobacco has been cut into crinkly shreds, it is subjected to the same treatment as straight-cut shreds, but subsequently when the crinkly-cut shreds are re-assembled in 10 the filler of a cigarette, as at 17, their form and their entanglement prevents them from packing as closely as straight-cut shreds. As a result of the crinkly characteristic of the shreds, as they are entangled in re-assem- 15 blage, a filler containing upwards of 10% less crinkly-cut tobacco than straight-cut to- bacco will expand and adhere to the paper wrapper and prevent the tobacco from fall- 20 ing out. And the same characteristic is re- sponsible for the more tortuous and more open draft passages which improve smoking properties.

What is claimed is:

1. The method of making cigarettes which 25 consists in cutting tobacco to form crinkly shreds, and subsequently forming and wrap- ping filler containing said crinkly-cut shreds.

2. A method of producing cigarettes, con- sisting in assembling a mass of superposed tobacco leaves, then cutting therefrom, on 30 crooked lines crossing the mass, slices of superposed crooked shreds, then separating the crooked shreds, then differently assem- bling separated crooked shreds to form a fluffy filler, then encasing the fluffy filler in 35 a wrapper.

3. A method of producing cigarettes, con- sisting in assembling and compressing a mass of superposed tobacco leaves, then cut- 40 ting from the compressed mass, on crooked lines crossing the mass, slices of superposed crooked shreds, then separating the crooked shreds, then differently assembling the sepa- rated crooked shreds to form a fluffy filler, then encasing the fluffy filler in a wrapper. 45

4. A cigarette comprising a wrapper, and an assemblage within said wrapper of shreds cut on crinkly lines from assembled tobacco leaves, separated, and differently assembled to form a fluffy filler. 50

In testimony whereof, I have signed my name to this specification.

WILFORD J. HAWKINS.
